UNITED STATES PATENT OFFICE.

GEORGE A. STEINER, OF SALT LAKE CITY, UTAH, ASSIGNOR TO STEINER SALES COMPANY, OF SALT LAKE CITY, UTAH, A CORPORATION OF UTAH.

TOWEL CABINET.

Application filed February 20, 1922 Serial No. 538,102.

To all whom it may concern:

Be it known that I, GEORGE A. STEINER, a citizen of the United States, resident of Salt Lake City, county of Salt Lake, State of Utah, have invented certain new and useful Improvements in Towel Cabinets, of which the following is a specification.

The object of my present invention is to provide a towel cabinet of simple, economical construction, from which all gears, drive chains or belts and the like are entirely omitted.

A further object is to provide feed or control rolls, so constructed that there will be either no contact at all between the clean towel and the roll which contacts with the soiled towel, or such contact will be so slight as to make practically no difference in the sanitary characteristics of the cabinet.

A further object is to provide a cabinet from which the rolls can all be easily and quickly removed without the use of tools of any kind.

Other objects of the invention will appear from the following detailed description.

In the accompanying drawings forming part of this specification,

Figure 1 is a vertical sectional view through a cabinet embodying my invention,

Figure 2 is a similar view, showing a modified construction,

Figure 3 is a detail view of one of the feed or control rolls removed from the casing,

Figure 4 is a vertical sectional view, showing ribs arranged circumferentially on the feed rolls instead of lengthwise thereof,

Figure 5 is a sectional view on the line 5-5 of Figure 4,

Figure 6 is a detail view, showing a modified construction of the feed or control rolls.

In the drawing, 2 represents the side walls of a cabinet, having a rear wall 3, a top 4 and a door 5 in the front through which access may be had to the interior. The side walls of the cabinet have horizontal grooves 6 therein, forming guides communicating with vertical grooves 7 extending down to a point near the bottom of the cabinet. A shaft 8 is adapted for insertion into these grooves and supports the clean towel roll 9. A similar shaft 10 is adapted to receive the soiled towel 11. Between the clean and soiled towel rolls I provide feed

or control rolls, the lower roll 12 having gudgeons 13 to fit and slide in the guides 6 and 7 and provided on its periphery with a series of longitudinally arranged ribs 14 between which are grooves 15, the outer faces of said ribs having a suitable material, such as sand paper 16 or cord belting may be used, for contact with the surface of the clean towel, so that when the user stands in front of the cabinet and pulls down on the loose end of the clean towel he will revolve the feed roll in contact therewith.

The other roll 17 has corresponding gudgeons to slide in the guideways and longitudinal ribs 18 with roughened surfaces 18 similar to those on the other roll, and the ribs 18 have grooves 19 between them adapted to receive the ribs 14 so that when the rolls are in engagement with each other, the ribs 18 will enter the grooves 15 but will not come in contact with the surfaces of the ribs 14 and consequently the ribs of the soiled towel feed roll will not contact with the clean towel to render it unsanitary or cause danger of infection to a user. The ribs 14 may contact with the bottoms of the grooves in the soiled towel feed roll, but these grooves will not become contaminated through contact with the soiled towel, as this portion of the towel will only engage the outer faces of the ribs 18 and as these ribs are at all points kept out of contact with the clean towel or with any portion of the clean towel feed roll which touches the clean towel, it follows that there will be no chance of soiling the clean towel before use or permitting any portion of it to become infected.

The soiled towel roll and the feed rolls will rest by gravity upon the clean towel and there will, therefore, be sufficient friction between them to insure the rotation of all the rolls when the user stands in front of the cabinet and pulls down on the clean towel.

A brace 20 is provided at the bottom of the cabinet, between which and the front door is a gap 21 for the feed of the clean towel and in the rear of the clean towel roll, I provide a brace 22 with which the soiled towel contacts and is directed to the soiled towel roll without any chance of contact with the clean towel.

In Figure 2 I have shown a modification which consists in omitting the soiled towel

feed roll entirely and allowing the roughened surfaces 16 of the ribs 14 to contact with the soiled towel and also with the clean towel. These points of contact are comparatively narrow and while this form of cabinet will not be as sanitary as the one shown in Figure 1, there will be comparatively little danger of soiling the clean towel or infecting it through the contact of this roll 10 with the soiled towel. In other respects the cabinet shown in Figure 2 is substantially the same as the one illustrated in Figure 1.

In Figures 4 and 5 I have shown another modification, which consists in providing 15 feed rolls 23 having a series of annular ribs 24 thereon and a similar roll 25 having ribs 26 which alternate with the ribs 24 and project into the gaps between these ribs. The relative position of the ribs is shown plainly 20 in Figure 5, where the ribs 26 are shown in contact with the soiled towel but do not contact with the faces of the ribs 24 of the lower feed roll, and hence there is no direct contact between the clean and soiled towel rolls. 25 The rolls are mounted one above another in the guideways in substantially the same manner shown with reference to the other figures. When the user stands in front of the cabinet and pulls down on the clean portion 30 of the towel, he will revolve the feed roll 23 and through the contact of the ribs 24 with the other feed roll 25, it will be revolved and its motion transmitted to the soiled towel roll through the ribs 26.

35 In Figure 6 I have shown another modification, which consists in providing a shaft 27 having spools 28 thereon provided with annular flanges 29 which have sand-papered or otherwise roughened surfaces to contact 40 with the clean towel. A similar shaft 27^a is mounted above the shaft 27 to slide in the grooves in the walls of the cabinet and narrow faced rolls 30 are mounted on the shaft 27^a and have roughened surfaces to contact 45 with the soiled towel, the rolls 30 being of suitable width to pass between the flanges of the spools 28, as indicated in the figure. Their surfaces, however, do not contact with the corresponding surfaces of the flanges 50 and consequently the contacting surfaces of the spools or the parts thereof which touch the clean towel will not be contaminated through contact with the rolls which touch the soiled towel, and thus the cabinet will

be thoroughly sanitary in the sense that the clean towel is kept out of contact with the soiled portion and all danger of infection of the clean towel, which might occur through engagement thereof with rolls which contact with the soiled towel, will be 60 eliminated.

In various other ways these feed control rolls may be modified in arrangement and construction and still be within the scope 65 of my invention.

I claim as my invention:

1. A towel cabinet comprising a casing, clean and soiled towel rolls mounted therein, feed rolls between said clean and soiled towel rolls and having co-operating peripheral ribs for driving one feed roll from the other, the ribs contacting with the soiled towel roll being out of contact with the surfaces of the ribs which contact with the clean towel roll. 70

2. A towel cabinet comprising a casing, clean and soiled towel rolls therein, feed rolls interposed between said clean and soiled towel rolls and having longitudinal peripheral ribs thereon with roughened faces, the ribs of one roll contacting with the clean towel and the ribs of the other roll contacting with the soiled towel and interlocking with the ribs of the clean towel feed roll without contacting with the faces thereof, whereby when the user exerts a pull on the clean towel the feed rolls will be revolved to wind up the soiled towel. 80 85

3. A towel cabinet comprising a casing having vertical guideways in its side walls, clean and soiled towel rolls mounted one above the other in said guideways, feed rolls between said clean and soiled towel rolls, each feed roll having a plurality of narrow peripheral ribs thereon provided with roughened surfaces respectively for engaging the webs of said towel rolls respectively, the ribs of one roll fitting between the ribs of the other roll, the ribs contacting with the soiled towel roll being positioned to be out of contact at all points with the surfaces of the ribs which contact with the clean towel roll whereby contamination of the clean towel roll from the soiled towel roll is prevented. 90 95 100 105

In witness whereof, I have hereunto set my hand this tenth day of February, 1922.

GEORGE A. STEINER.
